R. F. NIXON, JR

BASEBALL GLOVE

Filed May 22, 1925

Inventor

Robert F. Nixon, Jr.

By Spear, Middleton, Donaldson & Hall,

Attorneys.

UNITED STATES PATENT OFFICE.

ROBERT F. NIXON, JR., OF PHILADELPHIA, PENNSYLVANIA, ASSIGNOR TO GEORGE A. REACH, OF PHILADELPHIA, PENNSYLVANIA.

BASEBALL GLOVE.

Application filed May 22, 1925. Serial No. 32,075.

This invention relates to baseball gloves and particularly to the type known as fielders' gloves. The object of my invention is to provide an improved connection between the thumb and forefinger of such gloves, whereby the glove will be made to better withstand the strains to which it is subjected in practical use.

My invention is fully described in the following specification and pointed out in the appended claims.

In the accompanying drawings:—

Figure 1 is an elevation of a glove embodying my invention; Fig. 2 is a transverse section taken through the thumb of my glove;

Fig. 3 is an elevation partly in section, and

Fig. 4 is a detail view.

The numeral 1 indicates a glove which comprises a palm portion 2, fingers 3, and a thumb 4. The fingers 3 are made up of front and back portions 5 and 6 which have their edges in-turned and stitched together and to a welt strip 7 placed between the said in-turned edges to form a seam 8. The thumb 4 is stitched in the same manner along a seam 9. This construction is in common use and forms no part of my invention. In the preferred embodiment of my invention I provide a pair of web members 10 and 11, one of which is shown in detail in Fig. 4. The members 10 and 11 are made of suitable material, such as raw-hide, and each comprise a base portion A, having relatively long, narrow integral strap or thong portions B extending at

substantially right angles to the base A. In applying my invention to a glove, the members 10 and 11 are inserted into the inner seam of the thumb 4 and the adjacent seam of the forefinger 3, being placed on the welt strips 7 before the seams are stitched, so as to be incorporated in the seams 8, the strap portions B lying across the space between the thumb and forefinger of the glove. The meeting ends of the straps or thongs B are then secured together as by knots C, after the proper length has been determined. The thongs B may or may not be wrapped with adhesive tape D or otherwise covered, as for instance by elastic tubing.

It will thus be seen that I have provided a very strong and durable connection between the thumb and forefinger of a baseball glove, and one which can be readily made of requisite or desired length, and one which will better withstand the strains to which such a glove is subjected.

Having thus described my invention, I claim:—

1. In a glove having front and back finger and thumb forming portions seamed together, webs secured in the adjacent seams of the thumb and forefinger and integral thongs carried by said webs and having their free portions secured together.

2. The article of claim 1, in which the thongs are secured together by knotting.

In testimony whereof, I affix my signature.

ROBERT F. NIXON, JR.
